UNITED STATES PATENT OFFICE.

DAVID MCNAIR, OF BOSTON, MASSACHUSETTS, ASSIGNOR TO ROXBURY CARPET COMPANY, OF SAME PLACE.

DESIGN FOR CARPETS.

SPECIFICATION forming part of Design No. 11,683, dated March 16, 1880.

Application filed January 30, 1880. Term of patent 3½ years.

To all whom it may concern:

Be it known that I, DAVID MCNAIR, of Boston, in the county of Suffolk and State of Massachusetts, have invented a new and original 5 Design for Carpets, of which the following is a specification.

The nature of my design is fully shown in the accompanying photographic illustration.

I claim—

1. The design for a carpet, comprising the rectangular figure A, ornamented substantially as shown. 25

2. The design for a carpet, comprising the figures A C B, arranged and ornamented substantially as shown.

3. The design for a carpet, comprising the figures A C B, arranged and ornamented substantially as shown. 3

4. The design for a carpet, substantially as shown.

In testimony whereof I have signed my name to this specification, in the presence of two subscribing witnesses, this 23d day of January, A. D. 1880. 35

DAVID MCNAIR.
